UNITED STATES PATENT OFFICE.

EDWARD H. ANGIER, OF FRAMINGHAM, AND WILLIAM M. WHELDON, OF ASHLAND, MASSACHUSETTS, SAID WHELDON ASSIGNOR TO SAID ANGIER.

CARTRIDGE BELT.

Application filed August 15, 1918. Serial No. 248,994.

To all whom it may concern:

Be it known that we, EDWARD H. ANGIER and WILLIAM M. WHELDON, citizens of the United States, and residents, respectively, of Framingham and Ashland, county of Middlesex, State of Massachusetts, have invented an improvement in Cartridge Belts, of which the following description, in connection with the accompanying drawings, is a specification, like characters on the drawings representing like parts.

This invention relates to cartridge belts and the purpose thereof is to provide an efficient belt which, after use, may economically be thrown away without refilling.

Our invention will best be understood by reference to the following description of an illustrative embodiment thereof as shown in the accompanying drawings wherein—

Figure 1 is the top plan view of a portion of a machine gun cartridge belt partially filled;

Fig. 2 is a side elevation thereof with a portion broken away;

Figs. 3 and 4 are sections on the lines 3—3 and 4—4 respectively of Fig. 2; and Fig. 5 is an enlarged section on the line 5—5 of Fig. 2.

In Figs. 3 and 4 we have not attempted to show in the sections the laminated nature of the material as in Fig. 5.

In preparing our expendable cartridge belt we utilize a suitable material the base of which is paper and the belt as shown (see Fig. 1) comprises two strips or bands 7 and 9 placed together face to face and secured together at intervals by suitable means, herein illustrated as staples 11, to provide cartridge-receiving pockets 13. One end of the belt may be formed into or have secured thereto a tab 15 which serves as a handle to lift the belt and as a guide for introducing it into the machine gun in the first instance.

In order to provide a paper belt of sufficient strength and one which will resist moisture, we construct each of the bands 7 and 9, as indicated in Figs. 2 and 5, of two strips 17 and 19, of suitable strong paper secured together by waterproofing adhesive 21 indicated by the stippling in Fig.

2. This adhesive preferably is black asphalt. Embedded in the adhesive between the strips 17 and 19 are longitudinally extending reinforcing threads 23. Material prepared in this manner is of substantial strength and resistant to water. Preferably, moreover, as best shown in Fig. 5, we make each of the strips 17 and 19 of greater width than the complete width of the belt and fold the edges inwardly. The completed band 7 or 9 thus embodies at least four thicknesses of paper the inner two of which are substantially encircled and protected on all sides by the interposed layer of adhesive 21.

The customary cartridge is provided, as here shown, with a bottle neck and it is therefore desirable to shape the pockets to fit this neck. For this purpose we provide a beading at the edge of the bands 7 and 9 which will make the opening at one side of the pocket smaller to accommodate the neck as illustrated in Fig. 3. Preferably this beading takes the form of a short inturned fold 25 (Figs. 3 and 2). Conveniently, we infold the opposite edge in such manner that the folded portion 27 will extend over the fold 25 and to or substantially to the opposite edge of the belt. There is thus provided, as shown in Fig. 3, a band consisting throughout the major portion of its width of a double thickness of combined strip and having a beading comprising three thicknesses fitting the bottle neck of the cartridges.

The construction of the belt just described has a further advantage since it provides a smooth surface for the interior of the cartridge-receiving pocket, so that when the belt is being filled the bullet can slip readily through the pocket without danger of catching any of the folds therein.

The two bands 7 and 9 may be secured together in any suitable manner but we preferably adopt the means herein shown which also serves to restrict the openings of the cartridge-receiving pockets on the upper side of the belt, viewing Figs. 1 and 2, to adapt them to the bottle necks of the cartridges. Herein we provide wire staples 11 extending over the sides of the belt and having their legs 29 and 31 bent over the top edge thereof side by side. At the top edge

of the belt the staple, therefore, grips a greater length of paper than at the bottom edge and the opening between them is thus shorter and restricted to fit more or less closely the bottle neck of the shell. Conveniently the extremities of the legs are equally offset from the general plane of the staple so as to close the pocket symmetrically from each side. In the illustrated example the offsetting is slight so that the extremities lie substantially in contact. By referring to "side by side", however, we do not necessarily imply such contact.

Referring to Fig. 5, we preferably distribute the reinforcing strands 23 in such manner that, as shown, one will come at or substantially at the lowermost edge of the belt, thus reinforcing this edge directly against tearing strains. Conveniently, also, several threads will be grouped together in the beading formed by the fold 25 and the upper portion of fold 27, thus making an exceedingly strong band at the upper edge.

In order to facilitate opening of the pockets in the first instance to permit filling the belt, we conveniently crease the paper between the joining staples 11, as indicated at 33 in Figs. 1 and 2. It will be understood that when the belt is empty the two bands will ordinarily lie in face to face contact. By the provision of the creases 33, when it is desired to open the pockets to permit the cartridges to be inserted it is possible to push two points along the belt toward each other longitudinally thereof and the creases will cause the paper between adjacent staples to bend in opposite directions, providing a free access to the pocket, as indicated in Fig. 1.

40. A belt constructed as described may be produced at a cost less than the cost of refilling such belts as are now used and it has been found to be strong and resistant to the influences of moisture and wear.

45. Having described in detail a preferred embodiment of our invention, the principles exemplified thereby which we claim as new and desire to secure by Letters Patent, we shall express in the following claims:—

50. 1. A cartridge belt comprising a pair of strips secured together at intervals to provide cartridge receiving pockets, each strip comprising two thicknesses of paper secured together by a waterproofing adhesive and folded over at the edges of the strip to provide substantially a double thickness comprising interior laminations substantially enclosed by waterproofing material.

55. 2. A cartridge belt comprising a pair of strips secured together at intervals to provide cartridge receiving pockets, each strip including a central band of paper, a layer of waterproofing adhesive encircling the same and an exterior paper band secured by said adhesive.

3. A cartridge belt comprising two bands and means securing them together at intervals to provide cartridge receiving pocket comprising staples having legs bent over one edge of the belt side by side to provide a relatively narrow opening at that edge.

4. An expendable cartridge belt comprising two paper strips secured together at intervals to provide cartridge receiving pockets, a relatively short portion of one edge of each strip being folded inwardly between the strips and the opposite edges being folded inwardly between the strips and extending over said short portions.

5. An expendable cartridge belt comprising two paper strips, opposed edges of the strips along one margin of the belt being inwardly folded to provide a beading, the strips being secured together at intervals by staples having legs bent over said folded edges side by side to shorten the opening at said edges, the size of the pockets between adjacent staples being restricted by the beading provided by the inward folding of the edges of the strips.

6. A belt as defined in claim 4 wherein the securing is effected by staples having legs bent side by side over the edges having the short folds whereby to shorten the opening at said edges.

7. An expendable cartridge belt comprising two bands secured together at intervals to provide cartridge receiving pockets, each band comprising two thicknesses of paper united by a flexible waterproofing adhesive, one edge of each band having a comparatively short inward fold and the opposite edge an inward fold extending over said short fold, longitudinal strands in the adhesive including a strand adjacent said opposite edge and a plurality of strands in the superposed folds adjacent the first edge.

8. An expendable cartridge belt comprising paper strips secured together at intervals to provide cartridge receiving pockets, said strips being creased between the securing points to facilitate opening of the pockets.

9. A cartridge belt comprising two bands and means for securing them together at intervals comprising members, each exteriorly embracing the bands and extending over both edges thereof and clinched thereon.

10. A cartridge belt comprising two bands and means for securing them together at intervals comprising staples straddling an edge of the belt and having legs overlying the faces thereof in clinching relation.

11. A cartridge belt comprising two bands and means for securing them together at intervals comprising staples straddling an edge of the belt and having legs overlying the faces thereof in clinching relation and terminally bent over the opposite edge side

by side to restrict the opening between adjacent staples at that edge.

12. An expendable cartridge belt comprising paper strip in face to face contact secured together at intervals by members clinched over the edges and overlying a face thereof to provide cartridge receiving pock-

ets, the strips being creased between the securing points to facilitate opening of the pockets.

In testimony whereof, we have signed our names to this specification.

EDWARD H. ANGIER.

WILLIAM M. WHEILDON.
